UNITED STATES PATENT OFFICE.

CHARLES P. WOOD, OF NEW YORK, N. Y.

CONTINUOUS FURNACE AND PROCESS OF REGULATING ATMOSPHERIC CONDITIONS IN FURNACES.

1,297,629.

Specification of Letters Patent. Patented Mar. 18, 1919.

Application filed September 19, 1917. Serial No. 192,081.

To all whom it may concern:

Be it known that I, CHARLES P. WOOD, a citizen of the United States, residing at New York, county of New York, State of New York, have invented a new and useful Continuous Furnace and Process for Regulating Atmospheric Conditions in Furnaces, of which the following is a specification.

This invention relates to continuous furnaces and to a process for regulating atmospheric conditions in furnaces, particularly in those which are continuous or semi-continuous; for instance, of the "tunnel" type.

Continuous furnaces, particularly those of the tunnel type, have a pre-heating zone, a combustion zone and a cooling zone, through which the material is successively passed by mechanical means, while undergoing treatment. Such furnaces effect a great saving in labor, time and fuel, cost of operation, repairs, maintenance and interest on capital invested, because the process involved in their operation and the treatment of the material is continuous, or semi-continuous.

The object of the present invention is to provide an improved furnace and a process which will regulate the character of the atmosphere in that portion of a continuous furnace in which cooling occurs; for instance, in the cooling zone of a tunnel furnace.

The process is adapted for use in various metallurgical operations, and the heat treatment of glassware and other materials. While I expressly disclaim any intention to limit the application of the process, it is shown and described as used for the bright annealing of steel sheets, to which it is particularly applicable.

In the annealing of steel, particularly steel sheets, it has been found desirable to allow the steel to cool in a reducing atmosphere to prevent oxidation which causes discoloration and hard spots in the sheets. Heretofore the various methods which have been adopted with a view to securing this result, have generally been expensive and unsatisfactory in that they have required increased labor and fuel consumption.

In my furnace and process, while the material is passing through the cooling zone, it is enveloped in an atmosphere consisting entirely of unburned gas whose circulation is

regulated in such a manner that the air requisite for combustion of this gas is supplied in the general region where it is intended combustion of the gas shall occur, means being provided to prevent access of air to the cooling zone and thereby to insure against dilution of the gaseous prism which is designed to completely immerse the material being cooled. The products of combustion are taken off in any suitable manner and give up their heat to incoming material while en route to their point of escape.

My furnace and process contemplates the regulation of atmospheric conditions in the cooling zone where the unburned raw gas exists, because, after combustion occurs the character of the atmosphere is not subject to the nicely regulated adjustment possible prior to combustion, certain temperature changes and chemical actions involved in combustion preventing such regulation. It is possible, however, to regulate atmospheric conditions to some extent even after combustion has occurred by effecting the desired mixture of gases before combustion occurs and this mixture may also be highly preheated before the air or oxygen required for combustion is allowed to mix with the combustible gas.

My process is a continuous one as it contemplates the maintenance of the point of burning off of the end of the gas column or prism in the same general region by preventing the admission of air, except as regulated in the process itself, into the cooling zone occupied by the gas column when cars bearing the material being treated are admitted to, and removed from, the furnace. This exclusion of air when a car is admitted to, or removed from, the tunnel, prevents the "sneaking" back of outer air into the gas within the cooling zone, and it also prevents explosions.

When carrying out the process in a continuous furnace, for instance, one of the tunnel type, the cooling zone of the tunnel can be filled with unburned gas, supplied and regulated at will by suitable means. Provision is made to prevent access of air to the cooling zone and, consequently, the unburned gas will always drift in the direction of the stack, due to impulse supplied by the draft. As the column or prism of gas reaches the combustion zone, air is fed thereto under any desired regulation to

meet requirements for combustion and it is then ignited, as, for instance, by a pilot burner. Since the general direction of the draft is toward the stack and because additional raw gas is continuously supplied, under any desired regulation, to the column or prism of gas in the cooling zone an access of air to the cooling zone is provided, the air supplied to the gas in the general 5 region of the point of combustion will not circulate backward or penetrate the gas column in the cooling zone; consequently, combustion will occur only as the column of gas advances to the point or general 10 region where air is admitted to the furnace. The result is that the process involves the burning off of the end of a continuously drifting or advancing gas column at a maintained or relatively fixed region or point; 15 other gas being continuously supplied back of this point or region to maintain a gas prism of substantially constant proportions. Not only does this process supply heat producing means for operating the furnace but 20 it maintains a reducing atmosphere in the cooling zone in which the material, steel sheets for instance, is enveloped while undergoing cooling.

The process also contemplates the utilization, if desired, of the additional step of 25 special admission of gas at the delivery point of the furnace, to regulate conditions there should it be found necessary or desirable.

30 Air locks at the admission and exit points of the furnace afford the means for preventing explosions and for preventing admission of air to the gas prism or column when a car is admitted to, or withdrawn 35 from, the furnace.

Fuels for carrying out the process are 40 preferably gaseous, but these may be obtained from any gas producing means. Natural gas, coke oven gas, producer gas, 45 acetylene gas, hydrogen, gas made from crude oil, or any of the combustible gases may be applied to whatever operation these particular gases may be found applicable in carrying out the process.

50 The present process is applicable to some furnaces intended for operation for other purposes but which are not applicable at present to certain metallurgical or heat treatment operations because of the fact 55 that oxidation or carbonization or other actions would occur therein after the material had been brought up to the point of maximum temperature.

60 The furnace which is disclosed herein to illustrate the process, while embodying improvements, is an illustrative disclosure only, in so far as the process is concerned as other continuous, or semi-continuous, furnaces may be used; nor does the process 65 depend upon any particular mechanical

features of the furnace in which it is carried out. In the furnace disclosed a sand seal is shown for separating the hot upper sections of the furnace from the cool lower section in which travels the mechanical means for conveying the material or ware; other methods or means may be employed for making this division of upper and lower sections effective.

In the accompanying drawings— 75
Figure 1 is a side elevation of a furnace chamber used in carrying out my process; Fig. 2 is a plan view thereof; Fig. 3 is a longitudinal section; and Fig. 4 is a cross section on line 4—4, 80 Fig. 2.

The furnace comprises a tunnel 1 having a preheating zone 2, a combustion zone 3, and a cooling zone 4. The cooling zone 4 has ports, Fig. 3, to which fuel gas is supplied through ducts 5 which have suitable valves or dampers so that the supply of gas to the different points of the length of the cooling zone may be regulated as desired. The exact location of the gas ports to which 85 ducts 5 lead will vary with the purpose for which the furnace is to be used, but they will always be arranged to deliver the gas to the different points of the length of the cooling zone 4. The products of combustion are taken out of the tunnel 90 through the opening 7 into the stack 6.

Any suitable damper or dampers 6^a may be employed to regulate the draft through the tunnel and into the stack 6.

Air is admitted through ports 11 in the 100 combustion zone 3.

At the inlet of the furnace there is an air lock 8 and at the outlet there are air locks 9 and 10. The air lock 8 has doors 17 and 18. The doors 17, 18 may be operated from the exterior of the furnace by any suitable means, 17^a, 18^a, but the door 18 need not necessarily be operated from the outside because conditions in the air lock 8 are such that the operator can remain inside the lock after closing the door 17. When the door 18 is opened, the car which carries the material or ware to be treated may be pushed into the active length of the tunnel 105 by a transmission 19 of any suitable kind; the one shown consisting of sprockets and a chain with any convenient form of dog for engaging a portion of the car for pushing or pulling the car when the chain is operated. Succeeding cars push other cars 110 ahead of them, but other means for conveying the material may be employed without affecting the process.

The air locks 9 and 10 are provided with doors 14, 15, 16, which can be opened from the outside without admitting air to the locks. Any suitable means such as shown at 14^a, 15^a, 16^a may be employed for this 125 purpose.

A transmission 20, operable from the ex- 130

terior of the furnace, has dogs 21 adapted to engage a portion of the car so that the transmission picks up the car from the end of the train within the furnace, moving it more rapidly than the other cars and taking it into the air lock 9 when the door 14 is opened. The door 14 is then closed behind the selected car and door 15 opened and the car moved into the air lock 10 by the continued operation of transmission 20. The door 15 is then closed and the car may be taken out into the atmosphere on opening the door 16. By the use of two air locks, the cooling zone 4 is prevented from being placed in direct communication with the outside atmosphere and any inrush of air is thus prevented.

The air locks prevent admission of air into the cooling zone and body of gas therein contained, when a car is admitted to the tunnel. Explosions are thereby prevented; and, further, by thus preventing commingling of outer air with the gas in the gas zone, the point of combustion is maintained at the end of the gas column in substantially the same region at all times, thus preventing the air from "sneaking" back into the gas zone and negating the very effect (immersion of the material in a body of gas) which is the object of the invention. My process is a continuous one, as the point of burning off of the end of the gas column is maintained at all times regardless of admission of the cars to, and their removal from, the furnace.

Since a certain amount of space is required to provide perfect combustion and to insure freedom of draft throughout the combustion zone 3 and the preheating zone 2, these sections of the furnace may be wider than the cooling zone 4 in which the volume of gas should be kept as small as possible. The line A, Fig. 4, indicates the greater width of the pre-heating zone 2, while the line B indicates the lesser width of the cooling zone 4. This difference in size renders it possible to reduce the volume of gas maintained in the cooling zone 4 without affecting the character of the atmosphere and its regulation in the said zone. In a furnace of the character disclosed, the cars have a heat-resisting deck 24 which forms a division between the heated upper section of the furnace and the lower section which contains the mechanically moving parts which should be kept at a lower temperature in order to render the operation easy and practicable. I have shown a sand seal 25 to prevent circulation and the consequent transfer of heat from the upper to the lower section, but other means can be used without any change in the principle of maintaining a reducing atmosphere or an adjustable and regulable quantity of gas or gases in the cooling zone 4.

Operation: As the conveying means travels along the pre-heating zone 2 and approaches

the furnace or combustion zone 3, the ware or material carried thereby is gradually heated by absorbing heat from the products of combustion. The heat to be maintained is regulated by regulation of the amount of gas admitted into the cooling zone 4 through the ducts 5 and the amount of air admitted through the air ports 11. Having passed the combustion zone, the cars enter the cooling zone 4 which is completely filled with raw or unburned gas. The cooling zone is of such a length and so proportioned that the material under treatment therein has cooled down to the required temperature by the time the ware or material reaches the door 14.

If desirable in certain operations, the lock 9 may be filled with gas admitted through a port from a suitably controlled duct 22, while the conveyer is moving from the cooling zone 4 into the lock 9. The door 14 would then be closed and, if necessary or desirable, the gas could be taken out through a draft port 23. Resort need not be had to this step, but I refer to this feature to show the flexibility of operation under the process to take care of the most extreme requirements for maintaining a reducing atmosphere in the cooling zone of the furnace.

To insure against admission of air to the cooling zone I may provide any suitably controlled draft means 13 which may be either a stack or a fan or a combination of the two, adjustable by any well known means and carefully set by draft gages so that in case the discharge end of the furnace should have to be opened to the atmosphere, the draft would be so balanced that there would be no inrush of air to the cooling zone 4.

The cooling zone 4 being filled with unburned or raw gas, the draft causes the column or prism of gas to drift toward the preheating zone 2 and as the prism of gas reaches the combustion zone 3, it receives through the ports 11 the necessary air for combustion. Ignition may be started and maintained by pilot burners 12. Since the general direction of the draft is always toward the stack 6, and because additional gas is being supplied to the cooling zone 4 through the ducts 5, under any desired regulation, air will not tend to circulate back into the cooling zone. Consequently combustion occurs only in the general region where the gas is ignited in the combustion zone, that is, in the region where the air is admitted through the ports 11. The process contemplates, therefore, the continuous advance of a prism of gas whose end is burned off as it reaches a given point, additional gas being supplied back of this point to maintain a gas prism of constant proportions. After the point of maximum heat has been reached in the combustion zone, the ware or material is immediately enveloped in the raw

or unburned gas in the cooling zone 4. In the treatment of steel sheets, for instance, there is obtained in the cooling zone a reducing atmosphere which prevents oxidation and consequent discoloration and hard spots. Any other material may be treated by the process.

I do not limit the process to the use of a reducing atmosphere nor to the supply of 10 gas only to the cooling zone 4; air may be admitted through some of the ducts 5, or several gases may be introduced into the cooling zone and the proportions adjusted until the desired atmosphere is maintained 15 in the furnace.

What I claim is:

1. A process for regulating atmospheric conditions in furnaces, consisting in maintaining and advancing a gaseous body or 20 column, and burning off the advance portion of said body or column as said body or column progresses to a region where combustion is desired, while preventing access of air to the gaseous body or column other than 25 such as required for combustion, thereby maintaining a relatively fixed or maintained point of combustion of said gaseous column or body.

2. A process for regulating atmospheric 30 conditions in continuous or semi-continuous furnaces, consisting in maintaining a cooling zone comprising a substantially constant, continuously fed and continuously advancing gaseous body or column, maintaining a sub- 35 stantially fixed region of combustion by supplying air to the advance portion of said gaseous body or column and burning off said advance portion in the general region of the air supply as fast as said body or column 40 advances and preventing access of air to the gaseous body or column when the furnace is opened to admit or discharge the material about to be, or which has been, treated.

3. A process for regulating atmospheric 45 conditions in furnaces consisting in continuously advancing a gaseous body or column to a given combustion region of the furnace, continuously supplying air to, and burning off the advance portion of, said gaseous body 50 or column as it reaches said combustion region, continuously replenishing the gaseous body back of said combustion region as fast as the advance portion of the body is burned off and preventing access of air to the gaseous body or column other than such as is 55 required for combustion, thereby maintaining a gaseous body or column of substantially constant proportions having a rela-

tively fixed or maintained point of combustion.

4. A process for treating material in continuous or semi-continuous furnaces, consisting in first passing the material through a relatively fixed or constant combustion zone maintained at the advance portion of a body 60 or column of unburned gases the constituents of which are regulable both as to quantity and temperature, then through the unburned gases to effect cooling of the material while immersed therein, and, finally, out of the body of unburned gases, while preventing access of air to the gaseous body.

5. A furnace provided with a combustion zone, a cooling zone, means for admitting gas to the cooling zone and for maintaining 75 it there as a gaseous body or prism, means for supporting combustion of the advance end of the gaseous body in the combustion zone, and means for preventing access of air to the furnace when it is opened to admit or 80 discharge the material about to be, or which has been, treated, thereby preventing access of air to the gaseous body in the cooling zone.

6. A furnace provided with a combustion 85 zone, a cooling zone, means for admitting gas to the cooling zone and for maintaining it there as a gaseous body or prism, means for supporting combustion of the advance 90 end of the gaseous body in the combustion zone, and air locks at the entry and exit parts of the furnace which prevent access of air when the furnace is opened to admit or discharge the material about to be, or which has been, treated, thereby preventing access 95 of air to the gaseous body in the cooling zone.

7. A furnace provided with a combustion zone, a cooling zone, means for admitting gas to the cooling zone and for maintaining 100 it there as a gaseous body or prism, means for supporting combustion of the advance end of the gaseous body in the combustion zone air locks at the entry and exit parts of the furnace which prevent access of air when 105 the furnace is opened to admit or discharge the material about to be, or which has been, treated, thereby preventing access of air to the gaseous body in the cooling zone, and means for effecting any desired gaseous condition in the air lock at the exit portion of the furnace to regulate conditions therein.

In testimony whereof I hereunto affix my signature.

CHARLES P. WOOD.
